UNITED STATES PATENT OFFICE.

WILLARD T. SEARS, OF HARTFORD, CONNECTICUT, ASSIGNOR TO PRATT & WHITNEY COMPANY, OF HARTFORD, CONNECTICUT, A CORPORATION OF NEW JERSEY.

SUPPORTING-ARM FOR RADIAL DRILLS.

1,098,981.

Specification of Letters Patent.

Patented June 2, 1914.

Application filed October 12, 1912. Serial No. 725,417.

To all whom it may concern:

Be it known that I, WILLARD T. SEARS, a citizen of the United States, residing at Hartford, in the county of Hartford and 5 State of Connecticut, have invented certain new and useful Improvements in Supporting-Arms for Radial Drills, of which the following is a specification.

This invention relates to radial drills, one 10 of the principal objects of the invention being to provide a machine of this character having a drill-spindle supporting-arm which is strong in construction to thereby effectually adapt it to resist the bending and 15 the torsion due to vertical thrusts directed upwardly thereagainst initially by the drill or equivalent tool when in action.

In the drawings accompanying and forming 20 part of the present specification I represent one of the several forms of embodiment of the invention which to enable those skilled in the art to practise the same will be fully set forth in the following description. I do not, however, restrict myself to 25 this disclosure; I may depart therefrom in several respects within the scope of the invention defined by the claims following said description.

Referring to said drawings: Figure 1 is 30 a top plan view of a radial drill involving my invention. Fig. 2 is a side elevation of the upper portion of the same. Figs. 3 and 4 are transverse sections of the lines 3—3 and 4—4 respectively of Fig. 1. Fig. 5 is a trans- 35 verse sectional view showing an old type of supporting arm and my improved supporting arm superimposed thereon.

Like characters refer to like parts throughout the several views.

40 A radial drill usually comprises a vertical column, a supporting-arm, and a drill-spindle carrying head, said arm being generally horizontally disposed and supporting said head for adjustment longitudinally 45 thereof. This head in addition to the drill-spindle is supplied with the usual adjuncts for adjusting said head and the spindle. When the drill is in operation on the work there is considerable upward thrust applied 50 to the spindle which in turn transmits the same to said arm. Various ways have been devised for resisting the torsional and bending effects consequent upon this thrust. Theoretically an arm in the form of a tube

circular in cross section is practically perfect; to resist torsion, it has its disadvantages, however. A drive shaft for rotating, through intervening gears or equivalent means, extends along said arm and when the same is a circular tube the shaft must of necessity be mounted outside the arm; this construction is so complicated that its practical or commercial use is stopped. This particular difficulty has been overcome by making the arm in the form of a part tube or 55 of channeled form in cross section, thus materially decreasing its transverse area and providing at the same time a longitudinally-extending groove in which the shaft can be situated. Like this old type of arm my improved arm is in the form of a segment in 60 cross section. My arm though differs radically from the old in that I dispose the lower terminal portion of the same permanently to the rear of the upper terminal portion; I thus retain the groove, although it is 65 shallower than that in the old form, which is important in that I increase the distance materially from front to back of the arm, without increasing its weight. It will be 70 clear therefore, that the lower terminal portion of the arm is permanently or continuously back of the upper terminal portion thereof; that is to say this relation is always 75 present whether the arm is adjustable about an axis or not. In other words I can employ practically the same amount of material as is used in casting the old type of arm and greatly increase the resisting effect thereof, 80 both as to bending and torsional stresses. 85 While the groove in the front of the arm is highly advantageous it may not in all cases be necessary, the invention not being restricted in this respect. By making the 90 groove shallow as set forth I decrease the 95 possibility of its collapse, making it thereby very strong.

In the drawings the vertical column of the machine is denoted by 2 and it rises from a suitable base or other foundation (not 100 shown). This column constitutes the subject matter of a copending application filed October 2, 1912, Serial No. 725,416. The horizontal supporting arm is designated by 3 and it sustains for longitudinal adjustment the drill-spindle head 4 equipped with the usual accessories for adjusting said head and for also adjusting the rotary drill 105

spindle 5 which it is needless for me to describe. As will be perceived on reference to Figs. 3 and 4 said arm 3 is segmental in cross section and is preferably although not necessarily hollow. By having the arm 5 hollow I can make the same comparatively light without sacrificing necessary resisting ability. The said arm is tapered progressively on its rear side toward its outer, 10 although in all cases this is not essential. There is a rotary-shaft as 6 operable in practice from an electric motor or in some other suitable way, for driving through gearing or otherwise, the drill spindle 5, said shaft 15 as shown extending longitudinally of the supporting arm 3 in the groove or channel 7 in front of said arm 3. It will be observed that the lower terminal portion 8 of the arm 3 is back of the upper terminal portion 9 thereof by virtue of which I can give 20 to the outer wall a greater outward bulge and thereby make the arm of greater extent from front to rear than the segmental form of arm now in use without increase of weight or metal; as a result I increase the resisting 25 power both as to bending and torsional stresses, of said arm 3 with respect to the old type. The upper terminal portion of said arm is provided with ways 10 for supporting the head 4 for adjustment, the lower 30 part of said upper terminal portion being rabbeted as at 11 to receive the relatively fixed rack 12 constituting part of the adjusting means for said head. 35 It is desirable to note that the upper and lower terminal portions of the head supporting arm 3 have ways 15 and 16 for the slideable head 4, these ways as shown being vertical, the plane of the front of the lower way 40 being back of the plane of the front of the upper way. In the construction shown the lower way 16 is a greater distance from the axis of motion of the spindle 5, than the upper way 15, this axis being indicated by 45 the dotted lines 17 in Figs. 3 and 4.

As already explained the lower terminal portion of the supporting arm is back of the upper terminal portion thereof. It should also be stated that the metal resulting 50 from the positioning of said lower terminal back of said upper terminal can be distributed in the rear portion of said arm, for instance in the rear surface thereof by virtue of which said arm can be made of greater cross sectional extent than the old 55 form of arm but without any increase in weight and metal. In the construction shown the result is secured by making the radius of the rear surface of said arm 60 greater than the radius of the front surface or grooved portion thereof which, however, in all cases may not be necessary, such for example as when the arm has no groove in its front. This groove, however, is highly 65 advantageous in that it provides a space for

the power-transferring shaft 6 or equivalent. The mere setting of the lower terminal back of the upper terminal of said supporting arm is in itself highly advantageous as in view thereof I can bring the axis of rotation 70 of the spindle much closer in than is possible where the upper and lower terminals of the arm are in vertical alinement.

In Fig. 5 I have shown the new and old types of arms, denoted by 3 and 3' respectively. One of the primary considerations in a supporting arm is the ability thereof to resist the thrusts and torsion effects which the arm 3 does in a highly advantageous manner. This arm 3 is of the same 80 weight and has the same amount of metal as the arm 3', but is materially stronger, due to the fact that the lower portion or terminal of the arm 3 is back of the upper terminal thereof, by virtue of which said arm 3 85 or the outer wall thereof can be given a greater bulge or bow away from the axis of rotation of the spindle than is the case with the old arm. In other words in the new form of arm the increase in cross sectional 90 extent over the old is due to the fact that the lower terminal portion of the new form of arm is back of the upper terminal portion thereof, the difference in cross sectional extent representing the increase of thrust and 95 torque resisting ability of said new form of arm, and this without increasing the weight or amount of metal in said new form of arm 3. That is to say the metal displaced by setting the lower terminal back of the 100 upper terminal of said arm 3 is distributed in the rear or back part thereof.

What I claim is:

1. In a radial drill, the combination of a supporting arm having separate ways, a 105 head slideable on said ways, and a rotary spindle on the head, one of the ways being a greater distance from the axis of rotation of the spindle than the other way.
2. In a radial drill, the combination of a 110 supporting arm having superposed ways, a head slideable on said ways, and a rotary spindle on the head, the lower way being a greater distance from the axis of rotation of the spindle than the upper way.
3. A supporting arm for radial drills segmental in cross section, the lower terminal portion of said arm being back of the upper terminal portion thereof, the metal resulting 115 from the disposition of said lower terminal back of said upper terminal being distributed in the back part of said arm.
4. A supporting arm for radial drills segmental in cross section having a groove on the front side thereof and the rear side being curved, the upper terminal of said arm being in front of the lower terminal thereof, the metal resulting from the disposition of 120 said terminals being distributed in the rear surface of said arm, and said rear surface 125 130

being upon a greater radius than that of said groove.

5. A supporting arm for radial drills having upper and lower terminal portions provided with ways, a head slideable on said ways, and a rotary spindle on the head, one of the ways being a greater distance from the axis of rotation of the spindle than the other way, and the metal resulting from

this disposition of said ways being distributed in that part of the arm farthest from said axis of rotation. 10

In testimony whereof I affix my signature in presence of two witnesses.

WILLARD T. SEARS.
